John B. King, Jr.
WITNESS:

INVENTOR
Biaggio Santangelo
BY Victor J. Evans
ATTORNEY

UNITED STATES PATENT OFFICE.

BIAGGIO SANTANGELO, OF NORRISTOWN, PENNSYLVANIA.

TOY.

Application filed April 12, 1922. Serial No. 551,771.

To all whom it may concern:

Be it known that I, BIAGGIO SANTANGELO, a subject of the King of Italy, residing at Norristown, in the county of Montgomery and State of Pennsylvania, have invented 5 new and useful Improvements in Toys, of which the following is a specification.

This invention relates to toys and it has more particular reference to that form of 10 toy which is essentially provided with a rotary upper structure primarily intended to amuse children and others using the same.

The primary object of this invention is to 15 provide a toy of the nature above referred to which is adapted to operate a turntable by the travel of said toy over the ground or other appropriate surface, said turntable being in the nature of a box-like container.

20 Another object of this invention is to provide a wheel toy having a rotary upper structure, the same being simple in construction, cheap to manufacture and very entertaining in use.

25 With the foregoing and other objects in view as will be more clearly apparent from the following description, this invention essentially consists in the novel features of construction, combination and arrangement 30 of parts hereinafter fully described and more specifically defined by the appended claims.

In the further disclosure of the invention reference is to be had to the accompanying 35 sheet of explanatory drawings constituting a part of this specification and in which like characters of reference designate the same or corresponding parts in both the views.

40 Figure 1 is a central, vertical and longitudinal section through my novel form of wheel toy; and,

Figure 2 is an underside plan of the same.

Referring more particularly to the views 45 and in accordance with the embodiment of my invention illustrated, I construct a box-like underframe of wood or other appropriate material, the same comprising side members 3—3 and front and end members 50 4, 5 respectively. Disposed longitudinally in the lower part of the aforesaid box-like frame are spaced longitudinal braces 6—6 between which are transverse braces 7—7 and said box-like structure is appropriately 55 mounted on front and rear wheels 8, 9 respectively. These wheels 8, 9 are securely

mounted on the outer ends of transverse axles 10—10 appropriately journaled in the aforesaid box-like frame and likewise passing through the longitudinal braces 6—6 aforesaid. 60

Appropriately mounted on or forming an integral part of the aforesaid longitudinal braces are vertical uprights or bearings 11—11 on which is securely fixed a transverse platform 12, said platform 12 being provided at its central portion with a race or groove 13 for a purpose later on explained. Centrally longitudinal relative to the aforesaid box-like frame and appropriately journaled in the transverse braces 7—7 are longitudinal axles 14—14 having secured on their outer ends square toothed gears 15—16, the gears 15 being adapted to mesh into and be driven by correspondingly 75 shaped gears 17—17 keyed or otherwise mounted on the wheel axles 10. Transversely of the braces 6—6 and on the upper surface thereof I secure a bar 18 that constitutes the lower bearing for a vertical shaft 80 19, said shaft being fitted at its lower end with a gear 20 in mesh with the aforesaid gears 15 on the inner ends of the longitudinal axles 13—13. This vertical shaft 18 extends upwardly through the above referred to platform 12 and also through a turntable member 21 which is provided on its underside with a race 22 in register with the aforesaid race 13 and between these races 85 there is fitted a series of anti-friction balls 23. Secured in any appropriate manner to the upper face of the turntable member is the bottom 24 of a box-like structure 25 and it will be observed from an examination of Figure 1 more particularly, that the upper 90 end of the aforesaid vertical shaft 19 is fitted with a washer 26 and lock nut 27 whereby provision is made for the proper adjustment of the box-like structure 23 and turntable 21 relative to the platform 12. 100 Secured in any of the well known ways to the outside of the front 4 is a forked bearing 28 in which is hingedly mounted a tongue or draw-bar 29 whereby the toy may be propelled over the floor or other appropriate surface. 105

In use it will be readily apparent to those acquainted with the art that when the toy is pulled or pushed over a floor or other appropriate surface that the rotation of the axles 10—10 will impart rotation to the longitudinal axles 14—14 which through 110

the gears 16 and 20 will rotate the vertical shaft 19, the latter in turn causing the turntable 21 and its box-like structure 25 to be revolved. Obviously when the wheel 5 toy is pulled along the floor the box-like structure 25 will be rotated to the left hand or in a contra-clockwise direction and vice versa, when the toy is pushed over the floor or other appropriate surface the box-like 10 structure 25 will be rotated to the right hand or in a clockwise direction.

From the foregoing description and an examination of the drawing it will be clearly apparent that by my invention I have 15 provided a simple and cheaply manufactured and very amusing toy for the use and entertainment of children, as it will be obvious that a child may deposit a doll or other article in the box-like structure and be 20 considerably amused by its antics as the toy is propelled.

While there has been shown and described one practical embodiment of my invention it will of course be understood that various 25 changes may be made in the detail of construction, for instance—bevel gears may be employed instead of the square toothed gears shown and described, also the shape

and pattern of the understructure as well as the superposed rotary structure may be 30 varied without departing from the spirit and scope of the invention as more particularly defined by the appended claim.

Having described my invention, what I claim as new and desire to secure by Letters 35 Patent is:

A wheeled toy comprising a running gear structure including a rectangular frame and a pair of longitudinally extending parallel braces spaced equi-distant from the center of the frames, a plurality of cross braces connecting said longitudinally extending braces, driving shafts carried by said cross braces, driving axles carried by said frame and said longitudinally extending braces 40 and having geared connection with said driving shafts, a vehicle shaft having geared connection with said driving shafts, a platform supported from said frame, a turntable, said platform and turntable provided with ball races, and bearing balls in said races to permit free rotation of the turntable upon the platform.

In testimony whereof I affix my signature.

BIAGGIO SANTANGELO.
